UNITED STATES PATENT OFFICE.

LYMAN H. SNYDER, OF BRISTOL, CONNECTICUT.

DESIGN FOR A BICYCLE-HOLDER SPRING.

SPECIFICATION forming part of Design No. 28,755, dated May 31, 1898.

Application filed April 21, 1898. Serial No. 678,394. Term of patent 7 years.

To all whom it may concern:

Be it known that I, LYMAN H. SNYDER, a citizen of the United States, residing at Bristol, in the county of Hartford and State of Connecticut, have invented and produced a new and original Design for a Bicycle-Holder Spring, of which the following is a specification, reference being had to the accompanying drawings, in which—

10 Figure 1 is a plan view of a bicycle-holder spring, showing my design; and Fig. 2 is a side elevation of the same.

As shown in the drawings, the leading or material feature of my design consists of a 15 modified U-shaped spring made of flattened wire bent to the form shown. The back or bottom 3 of the U-spring is straight, and from it the two legs extend at right angles for a short distance in a straight line, as at 4, the 20 corners 5 at the junction of the straight back

and straight portion of the legs being slightly rounded, as shown. From said straight portions 4 each leg curves gradually outward, as at 6, and terminates in an outwardly-rolled coil 7, the inner end of each leg at the junction with its coil 7 being substantially in the line of the inner face of the straight portion 4. In the position shown in Fig. 2 the broader sides of the flattened wire are the vertical sides. 25

Having described my invention, what I claim as new, and desire to secure by Letters Patent, is—

The design for a bicycle-holder spring as herein shown and described. 30

LYMAN H. SNYDER.
